UNITED STATES PATENT OFFICE

GEORGE WILLENS, OF CHICAGO, ILLINOIS

ADVERTISING CLOCK

Application filed June 10, 1931. Serial No. 543,330.

My invention relates in general to advertising and more in particular to an advertising clock. The invention is in some of its aspects an improvement in the advertising 5 clock disclosed in my co-pending application, Serial #513,345, filed February 4th, 1931.

In general the advertising clock of my prior invention comprises a clock case having the usual clock face with hands driven by a suitable clock mechanism, preferably including a small synchronous motor and a time train for conveying the measured movement of the synchronous motor in proper relation to the hands. The clock frame also houses an advertising drum, the outer surface of which bears a plurality of advertising placards which are visible through an opening provided in the clock casing for this purpose. Mechanism is employed for partially rotating the drum at controlled intervals for displaying through the opening one advertising placard at a time. The mechanism for controlling the operation of the 25 drum is driven by the clock mechanism, in its preferred form from the synchronous motor.

A small synchronous motor of the type used in clocks is by its nature limited in power or torque and the drum must be driven in such a way as to consume as little power as possible, consistent with satisfactory operation. The drum driving mechanism must be capable of exact adjustment also, and the mechanism for securing this exact adjustment must take into consideration the limited power available and moreover must be inexpensive or the clock as an advertising medium defeats its own purpose. The relatively 35 fragile parts which must be employed to secure the results desired must not be such as to be thrown out of adjustment or broken by users of the clocks, who are apt to subject them to considerably more abuse than a manufacturer will intend.

Although the clock described in my prior application secures these advantages, I have found that I can improve the same in several respects.

Accordingly, the principal object of my

invention is to provide improved drum driving mechanism.

Another object is the provision of such mechanism which will consume a relatively small amount of power. 55

Another object is the provision of such mechanism which will permit simple and direct adjustment of the drum and the advertising matter thereon.

Another object is the provision of such a 60 mechanism which can be operated from power taken directly off of the second hand of the clock.

Another object is the provision of mechanism of this character which can be cheaply 65 manufactured and maintained.

Another object is to improve the construction of the drum itself.

Another object is to provide a direct relationship between the second hand of the 70 clock and the advertising mechanism.

Other objects and features of the invention will be apparent from a consideration of the following detail description, taken with the accompanying drawings, wherein 75

Fig. 1 is a front elevational view of the clock,

Fig. 2 is an irregular vertical sectional view taken through Fig. 1,

Fig. 3 is an enlarged fragmentary view 80 showing features of the drum driving mechanism,

Fig. 4 is a sectional view taken along the line 4-4 of Fig. 3,

Fig. 5 is a perspective view of a ratchet 85 lever forming part of the drum drive,

Fig. 6 is a transverse sectional view taken through the drum.

Fig. 7 is an enlarged fragmentary view 90 showing a detail of construction of the drum, and

Figs. 8 and 9 are enlarged fragmentary views showing modified constructions.

Referring now more in detail to the drawings, I employ a clock casing 10 having a clock case 11 and minute and hour hands 12 and 13, respectively, driven by a suitable time train 14, which in turn is actuated by a clock mechanism 16, preferably a small synchronous motor. The clock mechanism 16 is 10

shown schematically and includes gearing to drive a second shaft 17 at proper speed. The time train 14 transmits the motion of the shaft 17 to the hands 12 and 13, through suitable means well known in the art. The second hand 18 is driven directly from the shaft 17. Motion is transmitted from the clock mechanism to a drum 19, which carries advertising matter and which drum will be described more in detail hereinafter.

An escapement mechanism is employed in connection with the clock mechanism for changing the motion to a reciprocating motion, which motion through suitable means is conveyed to the drum.

The clock mechanism 16 is supported on a cross-bar 21; and pivoted to the cross-bar at 22 is a lever 23, which lever has a lever bar 24 carrying escapement pins 26 and 27. A star wheel 28 which turns with the shaft 17 is provided with star teeth 28a, which co-operate with the pins 26 and 27 to produce an escapement mechanism which causes a vertical reciprocation of the lever 23 when the shaft 17 is turned. In Fig. 3 this escapement mechanism is shown in the position that it occupies when the lever 23 is in substantially its uppermost position. The lever 23 is attached by means of a link 29 to a ratchet drive mechanism which transmits the reciprocating motion of the lever to the drum and rotates the drum partially, the amount of rotation being determined by the design of the machine. It is understood that the purpose of this rotation is successively to display advertising placards, each of which is supported on one of an equal number of subdivisions of the drum.

The drum comprises thin metal end plates 31 and 32, each formed with peripheral and annular grooves 31a and 32a facing each other, and a cylinder 33 preferably formed of relatively heavy paper. The ends of the cylinder extend into the grooves 31a and 32a and the drum as a whole is assembled by tie rods 34 extending through the drum and through apertures in the end plates, the ends being bent over as shown. This provides a very simple and economical but efficient construction and among the important features thereof is the conservation of weight.

A center shaft 36 extends axially through the drum and is secured to the clock casing by screws 37 and 38. Looking at Fig. 6, the right-hand side of the drum has a bearing 39 inserted in the end plate 32 on which the drum turns on the center shaft 36. A spacer 41 is disposed between the bearing 39 and the outer clock casing.

At the opposite end of the drum is disposed the mechanism which functions with the escapement mechanism previously described to impart the proper rotation and control to the drum. This includes a brake

bar 42, a ratchet lever 43, a hub 44 and a ratchet wheel 46 mounted together and co-operating with each other in a manner which will now be explained.

The hub 44 has a flange portion 44a disposed within the drum and adapted to bear against the end plate 31. The hub proper 44 is mounted on the center shaft 36 and carries the ratchet wheel 46 riveted thereto. A compression spring 47 is disposed around the hub 44 and has one end bearing against the ratchet wheel 46 and the opposite end bearing against the end plate of the drum. It will be seen from this construction that motion imparted to the ratchet wheel 46 will by the frictional engagement with the end plate 31 cause a rotation of the drum, but that the drum may be turned without relation to the ratchet wheel 46 as may be desirable for adjustment of the drum and for other purposes. In other words, a slip clutch drive connection is provided between the ratchet wheel 46 and the drum.

Now for imparting rotation to the ratchet wheel, I provide the ratchet drive lever 43 mounted on a hub 48 on the center shaft 36. The hub 48 is spaced from the hub 44 by a spacing lock washer 49, disposed in an annular slot in the center shaft 36. This spacing washer is secured in position in the following manner. Its inside diameter when applied permits it to pass over the center shaft 36 and it is slid over the center shaft to the annular slot, and is there merely collapsed with a pair of pliers to force two sides down into the slot. This makes a light but permanent assembly and one which will hold satisfactorily with the relatively small load placed upon it.

The ratchet lever 43 is pivotally connected at 51 to the link 29 and vertical reciprocable movement of this link imparts a rotary reciprocating motion to the ratchet lever. A ratchet drive spring 52 carried by the ratchet lever is adapted to engage in one of a plurality of peripheral slots 46a on the ratchet wheel 46. This drive spring 52 is disposed at an angle so as to engage in the slots in one direction to advance the ratchet wheel, but in the opposite direction to ride out of the slots without imparting motion to the ratchet wheel. In other words, a ratchet action takes place between the spring 52 and the ratchet wheel.

I provide positive means for anchoring the ratchet wheel and drum to the position to which they are moved by the ratchet lever. The brake bar 42 is mounted to the end of the center shaft 36 and bears against the clock casing. Its position between the clock casing and the end of the center shaft renders it substantially immovable, although it can be moved slightly if desired, to effect certain adjustments which will be explained. The brake bar carries springs 53 and 54 disposed

opposite each other and adapted to engage in the peripheral slots 46a on the ratchet wheel. The spring 54 is disposed in a plane substantially tangent to the ratchet wheel so that when it moves into a slot 46a it will prevent movement of the ratchet wheel in either direction. On the ratchet lever 43, however, I provide a spring release or depressing member 56, which as shown in dotted lines in Fig. 3, engages the spring 54 at substantially the time the ratchet lever drive spring 52 engages in one of the slots 46a to advance the ratchet wheel a distance equal to the distance between the slots. At this time when the advancement of the ratchet wheel 46 starts, the spring 54 is by this means held out of the slot in the ratchet wheel and the drive of the ratchet wheel proceeds without interference. The spring 53, however, is disposed at an angle so as to prevent back movement of the ratchet wheel 46. Its action takes place when the spring 54 has been released, but while the ratchet lever is still moving in a reverse direction before it is advanced for driving movement. Due to the slanting position of the spring 53, however, it does not hold when the ratchet wheel is advanced in a driving movement, but rides up out of the slot.

Before describing the operation of the driving mechanism for the drum, I shall refer to certain details of construction thereof, particularly with respect to supporting advertising thereon. As previously described, the cylinder 33 is formed preferably of relatively stiff paper or fibre board. Advertising matter is printed or otherwise shown on placards 57, (Fig. 7) which are a proper size to be seen completely through the opening in the casing. For securing the placards in position, I form tabs 58 from the material of the cylinder, these tabs being formed by partly cutting out a portion of the paper of the cylinder while the cylinder is in the form of a flat sheet of paper. When the paper is formed into a cylinder the tabs 58 tend to project partly so that the paper placards 57 can easily be inserted under the tabs.

The paper cylinder is snugly but not tightly secured at its ends by the end plates 31 and 32 and so the entire cylinder can be turned in the plates for adjustment purposes.

In the modification of Fig. 8, I secure the paper placards 57 in position by a paper strip 61 secured to the cylinder 33 by staples 62. This provides a projecting edge under which the placard can be extended. With this construction the paper cylinder also is secured between the end plates in the manner shown in Fig. 6.

Fig. 9 shows a still further modification of the drum cylinder for mounting the placards in place. The paper cylinder 133 has a portion 133a folded back on itself to form a longitudinal tab-like folded projection under

which the placard edges are adapted to be held.

When using the advertising device, the paper placards are secured to the outside of the drum in the manner shown, the number of placards corresponding with the number of teeth in the star wheel 26 and also with the number of slots in the ratchet wheel 46. Accordingly, when the drum is partially rotated, the entire placard is disposed in proper position, each one of the placards appearing in order at the opening to the clock casing. Once the driving mechanism has been set, the placards will continue to be displayed properly, due to the relationship between the number of placards and the character of the driving mechanism. Although I show six drive positions in the present embodiment, it is obvious that a greater or less number can be employed.

The drive is through a friction clutch arrangement, so if the drum is not in proper position the whole drum can be turned without affecting the driving mechanism in order to place the placard in proper position. When applying the placards to the drum, the drum can be rotated or held stationary in any way required by the operator to insert the placards without loss of time and without danger of injury to the driving mechanism.

One of the features of my present advertising clock is in connection with the second hand 18. Around the dial face there is a narrow circular band 65. I divide this circular band into a number of sections, corresponding to the number of advertising placards on the drum; in the present instance, six sections. Each one of these sections is given some distinguishing characteristic, as, for example, a different color as illustrated in Fig. 1. I then prepare the advertising placards to correspond to the designating or identifying characteristics of the individual sections of the band. For example, if a section of the band is red, the predominating color in the advertising placard which will be displayed at the time the second hand is pointing to this section, will also be red. This is an attractive novelty and advertising feature and is of value in connection with different styles of advertising. A company, which is running an advertising campaign in which the predominating color of their advertising is blue, for example, might contract for all of the blue space during a definite period. This arrangement with the second hand tells the observer in advance when a placard will be displayed, which he may be interested in. In this way it is obvious that the second hand and advertising drum operate together to secure a novel and useful result.

What I claim is new and desire to protect by Letters Patent of the United States is:

1. In an advertising clock, a clock mechanism having a driven shaft, a rotatable drum, means for supporting advertising matter on the drum, a pivoted lever, escapement mechanism on the shaft and lever for reciprocating the lever on its pivot, and connections from the lever to the drum for imparting movement to the drum.
2. In an advertising clock, a clock mechanism having a driven shaft, a rotatable drum, means for supporting advertising matter on the drum, a pivoted lever, escapement mechanism on the shaft and lever for reciprocating the lever on its pivot, and connections from the lever to the drum for imparting movement to the drum, said escapement mechanism comprising a pair of pins spaced from the pivot and displaced transversely thereof, and a star wheel on the drive shaft shaped to engage and depress said pins alternately whereby movement of the pins is effective to reciprocate said lever.
3. In an advertising clock, a clock mechanism having a driven shaft, a rotatable drum, means for supporting advertising matter on the drum, a pivoted lever, escapement mechanism on the shaft and lever for reciprocating the lever on its pivot, a drum actuating rod having one end pivotally connected to said lever, and a ratchet mechanism at one end of the drum and driven by said rod for imparting a partial rotation to the drum at each reciprocation of the said lever.
4. In an advertising clock, a rotatable drum adapted to bear advertising matter, a center shaft to which the drum is axially pivoted, a ratchet wheel rotatably supported on said center shaft and having equally spaced peripheral drive slots, a ratchet lever also pivotally supported on said center shaft, a ratchet drive spring carried by the ratchet lever and adapted to engage in said peripheral slots, means including a clock mechanism for reciprocating said ratchet lever whereby the ratchet wheel is also reciprocated, and friction means between the ratchet wheel and drum for imparting the movement of the ratchet wheel to the drum.
5. In an advertising clock, a rotatable drum adapted to bear advertising matter, a center shaft to which the drum is axially pivoted, a ratchet wheel rotatably supported on the center shaft, a compression spring disposed around the center shaft and between the drum and ratchet wheel, and ratchet means for driving the ratchet wheel, said drum being driven by the ratchet wheel through said spring, and said drum being permitted manual turning movement independent of the ratchet wheel.
6. In an advertising clock, a drum adapted to bear advertising matter, a center shaft to which the drum is axially pivoted, a ratchet wheel rotatably supported on said center shaft, a ratchet wheel having a ratchet drive spring adapted to engage said ratchet wheel, a brake bar having a spring for engaging the ratchet wheel, means for reciprocating the ratchet lever to drive the ratchet wheel, means for releasing the brake bar spring at each movement of the ratchet lever and means for imparting movement of the ratchet wheel to the drum.
7. In an advertising clock, a drum having end plates and a cylinder adapted to bear advertising matter, a center shaft to which the drum is axially pivoted, a ratchet wheel assembly including a hub rotatably supported on the center shaft, extending through an end plate of the drum, a flange around the hub adapted to bear against the inside face of the end plate, a ratchet wheel on the hub, a coil spring disposed around the hub and having one end bearing against the ratchet wheel and the other end bearing against the drum, and means for driving said ratchet wheel.
8. In an advertising clock, a drum having end plates and a cylinder adapted to bear advertising matter, a center shaft to which the drum is axially pivoted, a ratchet wheel assembly including a hub rotatably supported on the center shaft, extending through an end plate of the drum, a flange around the hub adapted to bear against the inside face of the end plate, a ratchet wheel on the hub, a coil spring disposed around the hub and having one end bearing against the ratchet wheel and the other end bearing against the drum, a ratchet lever rotatably supported on the center shaft, a ratchet drive spring carried by the ratchet lever and engaging said ratchet wheel and means including a clock mechanism for reciprocating said ratchet lever to drive the ratchet wheel and drum.
9. In an advertising clock, a drum having end plates and a cylinder adapted to bear advertising matter, a center shaft to which the drum is axially pivoted, a ratchet wheel assembly including a hub rotatably supported on the center shaft, extending through an end plate of the drum, a flange around the hub adapted to bear against the inside face of the end plate, a ratchet wheel on the hub, a coil spring disposed around the hub and having one end bearing against the ratchet wheel and the other end bearing against the drum, a ratchet lever rotatably supported on the center shaft, a ratchet drive spring carried by the ratchet lever and engaging said ratchet wheel and means including a clock mechanism for reciprocating said ratchet lever to drive the ratchet wheel and drum, a brake bar supported in alignment with the center shaft, having a brake spring adapted to engage the ratchet wheel, and means carried by the ratchet lever for releasing the brake bar spring at each reciprocation of the ratchet lever.
10. In an advertising clock, a drum having

end plates and a cylinder adapted to bear advertising matter, a center shaft to which the drum is axially pivoted, a ratchet wheel rotatably supported on the center shaft and having peripheral drive slots, a ratchet lever also pivoted on the center shaft and having a drive spring adapted to engage in said slots to drive the ratchet wheel, and pivoted drive lever, a link connection between said drive lever and ratchet lever, a clock mechanism, and escapement mechanism driven by the clock mechanism for reciprocating said drive lever, and a friction driving connection between the ratchet wheel and drum.

11. In an advertising clock, a drum having end plates and a cylinder adapted to bear advertising matter, a center shaft to which the drum is axially pivoted, a ratchet wheel rotatably supported on the center shaft and having peripheral drive slots, a ratchet lever also pivoted on the center shaft and having a drive spring adapted to engage in said slots to drive the ratchet wheel, braking means for the ratchet wheel including a stop spring adapted to engage the edge of the ratchet wheel, and pivoted drive lever, a link connection between said drive lever and ratchet lever, a clock mechanism, and escapement mechanism driven by the clock mechanism for reciprocating said drive lever, and a friction driving connection between the ratchet wheel and drum.

12. In an advertising clock, a drum having end plates and a cylinder adapted to bear advertising matter, a center shaft to which the drum is axially pivoted, a ratchet wheel rotatably supported on the center shaft and having peripheral drive slots, a ratchet lever also pivoted on the center shaft and having a drive spring adapted to engage in said slots to drive the ratchet wheel, a brake bar having oppositely disposed springs adapted to engage the ratchet wheel, one of said springs engaging to hold in both directions and the other of said springs adapted to hold to prevent reverse movement of the ratchet wheel, means on the ratchet lever for releasing one of said springs preparatory to advancing the ratchet wheel, and friction means for driving the drum from said ratchet wheel.

13. In an advertising clock, a clock casing, a clock mechanism in the casing, a clock face on the casing, the usual hour and minute hands driven by the clock mechanism and operating with the face to show the time, a rotatable drum within the casing, a plurality of advertising placards on the drum, each covering one of a number of equal sections of the drum, means for alternately moving the drum and holding the same stationary so as to display the advertising placards serially, a second hand driven by the clock mechanism, and markings disposed around the clock face in groups corresponding to the number of drum sections, whereby the adver-

tising placards may be made to harmonize and correspond with the markings indicated by the second hand.

14. In an advertising device, a rotatable drum having a number of equispaced advertising sections, means for rotating the drum to display the sections serially, a second hand, and a circular band around the hand having a number of sections corresponding to the drum sections.

In witness whereof, I hereunto subscribe my name this 22d day of May, 1931.

GEORGE WILLENS.
